SPINDLE SUPPORT FOR SPOOLS

Johannes Uyttenbogaart, Berlin - Lichterfelde, Germany, assignor to North American Rayon Corporation, New York, N. Y., a corporation of Delaware

Application January 25, 1937, Serial No. 122,297
In Germany February 8, 1935

11 Claims. (Cl. 242—18)

The present invention relates to winding spools but more specifically has for its purpose the provision of an improved rotatable support therefor.

In the winding of thread, yarn, etc., it is essential in many instances to wind the thread under an even tension throughout the winding operation. In order to accomplish this result it is necessary that the take-up speed of the thread be constant. As is well known, there are two methods for obtaining a constant speed of take-up. One method is to use a compensating gear arrangement whereby as the yarn body increases in diameter the speed of rotation of the winding spindle is reduced so that the peripheral speed of the yarn body remains constant. The second method makes use of the yarn body itself. The spool rests on a rotating cylinder and is driven thereby. By means of this latter method it is obvious that the peripheral speed of the yarn body remains constant and that further the necessity of having an expensive compensating gear arrangement is eliminated.

However, the use of yarn driven winding machines has certain disadvantages. As the yarn body increases in diameter the shafts of the spool holders, which rotate in grooves of bearing brackets, move upwardly. If, as is usual in the art, the shafts rotate in these grooves excessive wear results and replacement of the bearing brackets is necessary at frequent intervals and since in the winding of the threads even slight wear of these grooves causes uneven rotation of the spool and holder, uneven winding of the thread on the spool results.

The improved spool holder therefore is designed to rotate around its shaft and the shaft has merely a sliding movement in the groove as the yarn body builds up. This movement is so slow that the wear on the bearing grooves is slight.

The improved spool support comprises an inner basic body and two circular lateral flange members, which, due to their special construction not only support the spool but are adapted to hold it in proper operating position. The inwardly extending flange surfaces are tapered forming a frusto-conical surface which supports the spool while at the same time allowing the said spool to be easily removed therefrom. The outer portions of the flange members are shaped to form abutment flanges to hold the spool immovable in an endwise direction.

One of the said flange members is formed integral with or fixed to the basic member, while the other is removably mounted thereon for the purpose of exchanging spools.

An important feature of the present invention is the portion of the structure which relates to the mounting and removability of the removable flange member.

It is one object of the present invention to devise an improved rotatable support which will allow spools to be placed thereon and removed therefrom with a minimum of time and effort.

Another object of the present invention is to devise a rotatable support which while allowing the easy removal of spools therefrom will hold the said spools while in position thereon in positive rotative engagement with the said support.

Still another object of the present invention is to devise a spool holder which while holding the spool in positive engagement is adapted to rotate around a non-rotatable shaft.

These and other objects of the present invention will in part become obvious and will in part be pointed out in the following specification and appended claims when taken in conjunction with the attached drawings, in which,

Fig. 1 illustrates a longitudinal cross-section of the spindle support comprising the invention, with a spool mounted in position thereon; 25

Fig. 2 is a side elevation of the spool-holder and spool with the yarn body thereon and in position in the bearing brackets of a winding machine.

Fig. 3 is an end elevation of the parts shown in Fig. 2 with a portion of a driving roller also being shown in end elevation; and

Fig. 4 is a detail view of the bayonet slot arrangement for securing the spool in place on the spool holder. 35

In the drawings in which like numerals of reference indicate like parts, 1 and 2 indicate the bearing brackets of the winding machine, (not shown). The brackets 1 and 2 have grooves 3 and 4 into which the ends of a spool spindle 5 extend and ride therein as the yarn body 6 increases in diameter. The ends of the spindle 5 are flattened as shown at 5a to prevent rotation of the shaft in the grooves 3 and 4. With this construction the only relative movement between bearing brackets and shaft end is a slow sliding movement as the yarn body increases in diameter. On the spindle 5 is mounted a spacer sleeve 7 which may be pinned to the spindle 5 as shown at 7a. At either end of the spacer sleeve are mounted ball bearing races 8 and 9. Ball bearings 10 rotate in the said races 8 and 9 in bearing rings 11 and 12 mounted in a core member 13 which is adapted to rotate around the spindle or shaft 5. Washers 11a and 12a are provided to 55

retain the lubrication substance within the bearings.

At one end of the core member 13 is mounted a flange or shoulder member 14 which is attached thereto by any suitable means, for example as by being made integral therewith or by means of a set screw 14a. At the other end is mounted the removable flange or shoulder 15. The flange members 14 and 15 have tapered surfaces 16 and 17 which extend into and support a spool body 18.

The removable flange member 15 is slidably mounted on a tube 19 which may form an integral part of the disc 20. The tube 19 is slidably mounted on the core member 13 and attached thereto by a bayonet slot connection 21 as shown in Fig. 4 of the drawings. A coil spring 22 tends to force the flange member 15 inwardly against the spool body 18. A set screw 23 is provided to keep the flange member 15 from sliding off the end of the tube 19 during the removal of the said tube 19 from the spindle support.

The disc 20 as shown in the drawings, may be made large enough so that it protrudes over the spool to a considerable degree whereby it may be easily employed as a carrier disc for the winding thread. The periphery of the disc 20 may be provided with notches or abutments 24 adapted to receive and carry a thread therewith. The periphery of the disc 20 and the edges of the notches 24 may be rounded so that in carrying the thread unintentional breakage of the said thread will be prevented.

At the start of the winding operation the thread winding is facilitated by carrying the end of the thread across the periphery of the disc 20 whereby the notches of the disc catch the thread and carry it around the spool.

The spool body 18 carried by the spool holder 40 rests on a driving cylinder 25 and is rotated thereby.

In operation, when a new spool is to be fastened into position on the spindle it is first placed over the core body 13 and forced against the stationary flange member 14. The removable flange member 15 is then inserted in the spool together with the tube 19 and attached to the core member 13 by means of the bayonet slot connection 21. The spring 22 which is of the expansion type presses against the disc 20 and the flange member 15 thus holding the spool securely in position on the spindle core.

The advantages of this invention are clearly apparent. By using the spool holder illustrated in the accompanying drawings and described in the foregoing specification, the replacement of filled spools by empty ones is facilitated, and due to the novel structure of the said spool holder the shaft will not rotate in the bearing brackets, thus avoiding excessive wear therein, but the said spool holder and the spool will rotate around the said shaft with a minimum of friction, resulting in a more uniform yarn body than heretofore obtainable in the art. The locking means 21 permits ready removal of the tube 19 and disc 20 and yet when the said tube 19 and disc 20 are operatively attached to the spool holder it forms a positive connection which causes them to rotate with the said spool holder.

This application is a continuation in part of my copending application Ser. No. 61,335, filed January 29, 1936.

From a study of the foregoing description when made in conjunction with the attached drawings it is felt the complete construction, advan-

tages and operation of the invention will be clear to those skilled in the art to which it relates.

What I claim is:

1. A spindle support for spools comprising a shaft, a core member rotatably mounted on said shaft, an abutment flange at one end of said core member and having a surface adapted to support an end of a spool, a removable abutment flange at the other end of said core member 10 having a surface adapted to extend into the other end of the spool, and means to resiliently hold said removable abutment against said spool.

2. A spindle support for spools comprising a shaft, a core member rotatably mounted on said shaft, an abutment flange mounted rigidly at one end thereof and having a surface adapted to support one end of a spool, a removable abutment flange at the other end thereof having a surface adapted to extend into the other end of the spool, a tube member, said removable abutment flange slidably mounted on said tube member, said tube member having a disc formed integral therewith, a spring mounted on said tube member and bearing against said disc and said abutment flange, and means to attach said tube member to said core member.

3. A spindle support for spools comprising a shaft, a spacer sleeve fixedly mounted on said shaft, bearings fixedly mounted on said shaft 30 at ends of said sleeve, a core member, bearing races carried by said core and rotating on said bearings, an abutment flange mounted at an end of said core and having a surface adapted to support a spool, a removable abutment flange at 35 the other end thereof having a surface adapted to extend into the other end of the spool, a tube member, said removable abutment flange being slidably mounted on said tube member, said tube member having a disc formed integral 40 therewith, a spring mounted on said tube member and bearing against said disc and said abutment flange, and means to attach said tube member to said core member.

4. A spindle support for spools comprising a shaft, a spacer sleeve fixedly mounted on said shaft, bearings fixedly mounted on said shaft at ends of said sleeve, a core member, bearing races carried by said core and rotating on said bearings, an abutment flange mounted at one 50 end of said core and having a surface adapted to support an end of a spool, a removable abutment flange at the other end thereof having a surface adapted to extend into the other end of the spool, and means to resiliently hold said removable abutment against said spool.

5. A spindle support for spools comprising a shaft, means to retain said shaft against rotation, a core member rotatably mounted on said shaft, an abutment flange at one end of said 60 core member and having a surface adapted to support an end of a spool, a removable abutment flange at the other end of said core member having a surface adapted to extend into the other end of the spool, and means to resiliently hold said removable abutment against said spool.

6. A spindle support for spools comprising a shaft, a core member rotatably mounted on said shaft, an abutment flange mounted at one end 70 of said core member and having a surface adapted to support an end of a spool, a removable abutment flange at the other end of said core member and having a surface adapted to support the other end of the spool, a tube member 75

mounted on said core member and carrying said removable abutment flange, and a disc mounted at one end of said tube member, said disc being of a diameter larger than that of the said spool, and means to resiliently hold said removable abutment against the spool.

7. A spindle support for spools, comprising a shaft, a core member carried on bearings on said shaft, an abutment flange at one end of said core member adapted to carry an end of a spool, said flange having a tapered surface adapted to be positioned between the core member and the spool, a removable abutment flange at the other end of said core member having a tapered surface adapted to be positioned between the core member and the spool, and means to resiliently force said removable abutment toward said spool.

8. A spindle support for spools, comprising a shaft, a core member carried on bearings on said shaft, shoulder means fixed to said core member for retaining one end of a spool on said core member, means removable from said core member and having also a shoulder thereon for retaining the other end of said spool on said core member, and resilient means for retaining said removable means in position.

9. A spindle support for spools comprising a shaft having a flat face formed thereon near each end, a spacer sleeve fixedly mounted on said shaft, bearings mounted on said shaft at ends of said sleeve, a core member, bearing races carried by said core and rotating on said bearings, an abutment flange mounted at one end of said core and having a tapered surface adapted to support a spool, a removable abutment flange at

the other end thereof having a tapered surface adapted to extend into the other end of the spool, and means to resiliently hold said removable abutment against said spool.

10. A spindle support for spools comprising a shaft having flat co-planar faces near its ends, a spacer sleeve fixedly mounted on said shaft, bearings mounted on said shaft at ends of said sleeve, a core member, bearing races carried by said core and rotating on said bearings, an abutment flange mounted at one end of said core and having a tapered surface adapted to support a spool, a removable abutment flange at the other end thereof having a tapered surface adapted to extend into the other end of the spool, and means to resiliently hold said removable abutment against said spool.

11. A spindle support for spools comprising a shaft having a flat face formed thereon near each end, a spacer sleeve fixedly mounted on said shaft, bearings mounted on said shaft at ends of said sleeve, a core member, bearing races carried by said core and rotating on said bearings, an abutment flange mounted at one end of said core and having a tapered surface adapted to support a spool, a removable abutment flange at the other end thereof having a tapered surface adapted to extend into the other end of the spool, a tube member, said removable abutment flange slidably mounted on said tube member, said tube member having a disc formed integral therewith, a spring mounted on said tube member and bearing against said disc and said abutment flange, and means to attach said tube member to said core member.

JOHANNES UYTENBOGAART.
